The ornamental design for a LED light bar, as shown and described.

DESCRIPTION

FIG. 1 is a perspective view of a LED light bar showing my new design;

FIG. 2 is another perspective view of the LED light bar thereof;

FIG. 3 is a front elevational view thereof;

FIG. 4 is a rear elevational view thereof;

FIG. 5 is a right side view thereof;

FIG. 6 is a left side view thereof;

FIG. 7 is a bottom plan view thereof;

FIG. 8 is a top plan view thereof; and,

FIG. 9 is an enlarged view of portion 9 of FIG. 2 thereof. The broken lines in the drawings illustrate portions of the LED light bar which form no part of the claimed design.
